DESIGN FOR A WATCHCASE

Macy H. Stein and Max S. Stein, New York, N. Y.

Application June 11, 1936, Serial No. 63,232

Term of patent 14 years

To all whom it may concern:

Be it known that we, Macy H. Stein and Max S. Stein, citizens of the United States, residing at 1 Seaman Avenue, in the county, city, and State of New York, have invented a new, original, and ornamental Design for a watchcase, of which the following is a specification, reference being had to the accompanying drawing, forming part thereof:

Fig. 1 is a perspective view in elevation;
Fig. 2 is an end perspective view;

Fig. 3 is a front perspective view; and
Fig. 4 is a rear perspective view of a watchcase, showing our new design.

Figs. 1 and 2 show the watchcase in closed positions while Figs. 3 and 4 show the same in open positions.

We claim:

The ornamental design for a watchcase, substantially as shown and described.
